(57) **CLAIM**

The ornamental design for a coin display tower, as shown and described.

DESCRIPTION

FIG. 1 is a top and front perspective view of a coin display tower showing my new design;

FIG. 2 is a front elevation view thereof;

FIG. 3 is a side elevation view thereof;

FIG. 4 is a rear elevation view thereof;

FIG. 5 is a top plan view thereof; and,

FIG. 6 is a bottom plan view thereof. A "Lazy Susan" rotating mechanism is shown in broken lines and is not part of the design.
